SHAVER WITH HAIR RAISING BRUSH

John T. Scully, New York, N. Y.

Application October 11, 1949, Serial No. 120,783

8 Claims. (Cl. 30—34)

My invention relates to improvements in shavers in which relatively movable members cooperate to clip off or shear-cut hair or hairs, such machines being referred to in the art as dry shavers, hair clippers, shaving machines or shearing devices or the like, such devices being employed for shaving without the use of soap lather or shaving cream.

Important objects of this invention are: to provide means in a shaver to remove soot, grit, sand and the like from the beard and skin of the user, and thereby avoid consequent damage to the shearing head; to provide said means in a form for use to clean the beard and skin either while the motor is idle in the shaver, thus preserving it against wear, heating up and the unnecessary use of electric current, or for use simultaneously with the shaving operation and, thereby, save time by the combined shaving preparation and operation. A principal object is to provide said means in a form to increase the opportunity of relatively long hairs, or hairs curled on, or hairs lying substantially flat to, or in engagement with, the outer surface of the skin to enter the hair-receiving openings of the shearing head; another principal object is to speed up the time of the actual shaving operation; another principal object is to provide the means in a form to taunt the skin during the shaving operation and thus improve the closeness of the shave and, further, to quicken the time of a close shave. Further important objects are to provide said means in a convenient and economical form; in some instances in a form for adjustable location relatively to the shearing head; in some instances in a form for movement towards or away from the shearing head so that the means may be used simultaneously with the shaving operation or the shaving operation performed by itself on certain facial parts without the use of the means. Other important objects are to provide said means in the form of an attachment quickly and easily mountable on, or demountable from, a shaver, in some instances without the use of a tool; in some instances to provide the attachment as adaptable to be fitted on either of opposite sides of the shaver with said means disposed opposite the shearing head; to provide said means in a form in which working portions may be replaced by reversal thereof; to provide fastening parts whereby said means may be easily and quickly renewed in the attachment; in some instances to provide cushion-parts in the attachment for said means; to provide abutments in the attachment suitable for engagement with flat, curved or corrugated portions of the outer surface of the casing housing the motor of the shaver to properly position said means relatively to the shearing head; to provide a simply constructed, economically manufactured and an efficient attachment for the purposes outlined.

These objects above and others which will hereinafter become apparent are attained by the means and members shown in the accompanying drawing and described herein with reference to the drawing, and in which:

Similar reference characters refer to similar parts throughout the several views.

Referring more particularly to the drawing and, first, to Figs. 1 to 4 inclusive:

The shaver illustrated has the well known type of electric motor to vibrate a cutter actuating bar, the bar having its upper end received in a slot in the movable inner cutter of the shearing head, whereby vibration of the actuating bar causes the inner cutter to be longitudinally reciprocated for shearing cooperation with the outer shear member. The motor is housed in a casing, serving also as a handle, which is longitudinally divided into casing sections 20 and 21, respectively, the division being indicated along line 22, and these sections are fastened together by laterally spaced upper screws 23 screwed into section 21 and by laterally spaced lower screws, generally designated 24. At the lower end of the casing is electric current conductor cord 26 to conduct current to the motor. At the upper end of the casing is the shearing head in which channelled outer shear member 27 is provided on opposite sides of its channel with a series of spaced hair receiving slots 28 which extend outwardly in the top portion of the member and substantially rectangularly down into the side portions thereof and form combing and shearing bars 29 in the member. Beneath member 27 and urged into intimate engagement with the inner surface thereof is cooperating and channelled inner cutter 30 having on opposite sides of its channel a series of spaced cutting teeth 31 which cooperate in the shearing action with the inner portions of combing and shearing bars 29.

The inner cutter receives in a slot in the bottom wall of the channel the upper end of an actuating bar which is vibrated by the motor to reciprocatingly move the inner

cutter. The outer member is secured to the casing by the engagement of its ends into end fastening members 32 which, in turn, are secured to the casing by screws engaging square nuts pocketed against turning in the casing and between the two sections thereof; thus secured, the outer shear member, indirectly, holds the springs, urging the inner cutter, under compression. This shearing head is well known in the art. Detachably and adjustably mounted on the shaver, on the casing thereof, is a hair up-raising brush generally designated by 33 and of substantially cylindrical segmental shape in cross-section and having a radial-like formation of flexible bristles 34 held in said formation by and between the strands of wire twisted one upon the other, in the well known manner of the common wire twisted brush. At opposite ends of twisted wire portion 35 of brush 33 are fastening loops 36, one of which is formed closed and of generally circular shape by the wire twisting step in the manufacture of the brush while the other loop is first formed as a general loop disposed between the bristle portion of the brush and the tail end or twisting end of the twisted wire and in cutting off the tail end of twisted wire this general loop is cut into to a predetermined extent and thereby opened; then, the cut ends are bent towards each other on a cylindrical bar of the desired diameter, to make this loop of substantially the same size as the first closed loop, until the free ends are opposite and adjacent each other; then, the joint between the free ends, or of the free ends, is formed by soldering as indicated at 37 to close the loop, or, if desired the joint may be formed by any other suitable means or method. Brush 33 is secured to a brush carrier or supporting member, generally designated, 38 having a brush positioning member 39 in the form of a generally U-shaped rigid steel frame, the spaced cylindrical arms 40 of which extend substantially parallel to each other from the cross-portion 41 which, in this instance, is shown preferably, but not necessarily, flattened symmetrically on opposite sides throughout its central portion. At their upper ends, arms 40 have threaded holes 42 receiving the threaded shanks, extending through loops 36 of brush 33, of flanged headed fastening screws 43 to detachably fasten the brush on brush positioning member 39, the screw shanks being movably but suitably closely received in the fastening loops 36 to hold the brush substantially straight with arms 40. Carrier 38 also has a fastening or securing member or portion generally designated by 44 and of suitable, flexible, elastic material and since, as will be observed (Fig. 3), the outer surface contour of the shaver casing slants perceptibly inwardly from the central portion thereof towards the head and plug ends, respectively, of the casing, member 44 is formed of an elongated strip folded and crossed upon itself to form bottom band loop 45 and acutely disposed flexible arm extensions 46 and at the diamond shaped junction 47 of band loop and arm extensions the outer surface of the underlying portion of the strip and the inner surface of the overlying portion thereof are securely cemented or otherwise fixed together; on the outer ends of the arm extensions 46 are hollow or tubular fastening ends 48 internally receiving the arms 40 of positioning member 39 and formed, as shown herein, by folding or looping, intermediate their ends, marginal end portions of extensions 46 around, and cementing them as completely around as possible to, flexible rubber tubes 49 and then cementing the remaining end portions securely together to form the double layer portions on each extension and which extend approximately as far back as indicated by dash lines 50. Tubular ends 48 provide, in positioning member 39, cushions on arms 40 of "non-slip" rubber to abut the casing handle, that is, provide a cushioned casing-abutting face on member 39 and also serve, together with tubes 49 not only to space the bristles of the brush from the hair-receiving zone of

the shearing head of the shaver, but, also, to space the crossbar portion 41, between the cushioned arms, of member 39 from the casing-handle. Since arm extensions 46 are connected to the cushioned arms of member 39 and are connected at the junction 47, they form, together with the positioning member a fastening loop for telescopically receiving the handle, the arm extension 46 being a fastening band loop portion or fastening member and, because of the flexibility and elasticity inherent in the material of the band loop, the positioning member 39 is adjustable on the handle of the shaver relatively to the shearing head without the necessity of moving carrier 38 as a whole for making certain adjustments of the brush relatively to the shearing head. The material, with the exception of tubes 49, from which member 44 is made and has, up to date, been found the most suitable commercially available material to really grip the slippery surface of a streamlined shaver casing, and also present an attractive appearance, has rough opposite surfaces and is a non-skid sponge rubber marketed by the Fabrics Division of the E. I. Du Pont de Nemours & Co., Inc. At the time of cutting this material into strips from the roll the strips are cut in the direction in which the material is the more elastic or resilient. The upper ends of fastening ends 48 provide a rubber cushion for the twisted portions of the wire between the bristles of the brush and the fastening loops thereof, and are substantially flush with the ends of arms 40, and fastening ends 48 are relatively long enough and the tubes 49 therein fitted tightly enough on positioning member 39, but forcibly turnable thereon, to maintain this substantially flush end arrangement. Member 44, as shown herein, is stretched and, therefore, under tension, in both portions 45 and 46, and extensions 46 are resiliently, but firmly, holding member 39 drawn towards the shaver casing and with the portions of fastening ends 48 between arms 40 and the face of the side of the casing compressed against the casing and seating the brush in proper position; the distance which arms 40 are spaced from each other is related to the width of the side face of the shaver casing in the region thereof adjacent the shearing head and to the thickness and shape of ends 48 in order that the brush will be positioned substantially axially straight with the shearing head, parallel with the side thereof, and axially spaced therefrom a suitable distance, in accordance with the length and flexibility of the bristles, to prevent the bristles, when flexed in the direction towards the shearing head by their travel on the skin, from entering and blocking the hair-receiving openings in the outer shear member or engaging any comb portions on the combing portions of the combing and shearing bars thereof. The brush may have any suitable bristles, natural or synthetic, of any suitable length for non-irritating, or substantially non-irritating, travel on the skin in the manner and for the purposes herein described.

Use and operation: It will be clear that the user may employ any available segmental portion of the brush, using the shaver casing as a handle, to brush dust, grit and the like out of his beard and off his skin before starting relative movement of the shear-cutting members. By moving the shaver on the skin with the free ends of the bristles of the top of the brush travelling on the skin and the shaver being moved in the direction in which the brush is leading the shearing head, with the top of the shearing head in engagement with the skin simultaneously with the bristles of the brush and the cutters working, he may save time by performing the brushing of his beard and skin simultaneously with the shaving operation and remove damaging foreign matter out of the path of the cutters and, at the same time, especially when the shaver is moved in the direction opposite to the direction of hair growth, the hairs of the beard will be brushed up from the skin to facilitate their entrance into the hair-receiving openings in the shearing head, to increase the opportunity of the

combing portions of the outer shear member to comb the hairs into said openings, and the skin will be tautened for closer shaving; in this action, hairs bent backward to their direction of growth by their engagement with the brush bristles will, upon release, spring back through the space between the ends of the bristles, which are flexed on the skin, and the shearing head towards the shearing head in an effort to resume their original positions and, consequently, the beard hairs can enter the openings in the shearing head in their most erect positions and at the very time while the very localized area of skin surrounding any given of such hairs is a part of the tautened skin area and thereby improve the closeness of the shave, and since short hairs will be released more quickly and will spring back faster than long hairs, the daily shaver can catch his short beard hairs in their most erect position and at the same time speed up the time of his shave by moving the shaver faster on his skin than normally, and many backwardly bent long hairs whose ends are still engaged by the brush bristles will present released arched portions, equivalent for shaving purposes to an erect hair, in the said space for entrance into the openings of the shearing head, and curled hairs will be uncurled sufficiently, or entirely, for entrance into the shearing head openings. It will be clear, also, that the movement, by the user, of the shaver on the skin with the brush leading the shearing head will cause the bristles, engaged on the skin during the simultaneous travel thereon with the shearing head, to be flexed in the direction opposite to the direction in which the shearing head is moved on the skin, that is, the bristles engaging the skin will be flexed towards the shearing head. When so flexed, the free ends or tips of the bristles will be spaced not only from, or ahead of, the movable or inner cutter of the shearing head, but, preferably, will also be spaced from, or ahead of, the hair-receiving zone of the shearing head, with the results that the flexed bristles will not interfere with the hair-shearing action of the shearing head and will not block the hair-receiving openings in the hair-receiving zone of the shearing head, but will leave a space between the hair-receiving zone and the flexed bristles for easy entrance of erected hairs into the shearing head. This relative direction of flexure of the bristles is important because hairs, especially short hairs, of the beard will be erected and held erected as close to the hair-receiving zone of the shearing head as is practicable without blocking the openings thereof and, whereby, the on-coming shearing head will receive the hairs in the desired erected positions. For replacement of the working bristle portions at the top of the brush, screws 43 can be unfastened, the brush endwise reversed by turning upside down and fastened again; similarly, the brush may be renewed. To dismount the attachment from the shaver, ends 48 are seized and pulled outward and lifted over the shearing head, then bottom band loop 45 is further expanded to loosen its engagement with the casing and the attachment removed off the plug end of the shaver; to remount the attachment, the procedure is reversed. To use the side of the shearing head which is adjacent the brush for shaving the upper lip in the region of the nose or for aligning or trimming the sideburns or mustache, the user may seize cross-portion 41 with his finger and pull the positioning member 39 downwards and, thereby, the brush downwards out of the way temporarily retract the brush from the shearing head to fully expose the side of the head to prevent the brush from engaging the nose or blocking the user's mirror view or the like and then reseat the brush in proper position by seizing ends 48 to lift them up again, or, if preferred or necessary, these adjustments can be made by the same hand that is used in gripping the handle, for example, a finger of the gripping hand can be used, by crooking it, to seize cross-portions 41 and pull down the brush, and a finger can be used to push it up again; by manipulating positioning member 39 up or down he can vary the height of the top bristles rela-

tively to the shearing head, and, as the ends of these top bristles become worn down by repeated usage, he can adjust the brush upwardly to compensate therefor. The feature of the up or down, or vertical, adjustment of the brush while the bristles are disposed alongside the shearing head for simultaneous travel with the head on the skin, rather than a fully retracted adjustment from the head, is desirable, in some instances, to vary the pressure of the bristles on the skin by varying the extent to which they are flexed by their engagement with the skin in their simultaneous travel thereon with the shearing head, and desirable for accommodation to a variation of the pressure on the skin which the user may wish to employ on different parts of the face, for example, a lighter pressure on more tender areas such as the neck, or on sunburned areas or otherwise damaged areas; further, this vertical adjustment of the height of the brush relatively to the head for simultaneous travel on the skin therewith enables the user to make such adjustment as will accommodate the brush and head to the angle at which he prefers to hold the handle to the skin for shaving various parts of the face. This up or down adjustment of the brush is, it will be understood, not necessarily vertical in the absolute sense as to direction, but vertical in the sense of the relativity of the direction, irrespective as to whether the shearing head is supported on the end of the handle or on a side thereof. Since it will be observed, upon particular reference to Fig. 3, that the cross-bar of positioning member 39 is spaced from the handle and extends below ends 48, it will be clear that the user may by a sufficiently strong inward-downward push on the crossbar cause the brush to be tilted or rocked slightly outwardly, or laterally, away from the shearing head to widen the space between the bristles of the brush and the hair-receiving zone of the head for the purpose of providing better opportunity for a longer hair, or the hairs of a beard of longer growth, to enter the hair-receiving zone of the head in an erect or upright position during the simultaneous travel on the skin of the brush bristles and the shearing head. The lower ends of ends 48 serve as heels on which member 39 may be tilted or rocked and the extent of the tilt or rock and the pressure of push required depend, in this instance, on the degree of softness or hardness of tubular ends 48. This tilting or rocking feature may be more easily performed and to a wider extent in certain modifications of the positioning member hereinafter described. To temporarily maintain the brush in tilted adjustment it is necessary for the user to hold the crossbar pushed in because, upon release, the brush is pulled back again by the tension of the fastening band.

Referring further to Figs. 1 to 4 inclusive: Cylindrical brush 33 may be rotatably reversed on arms 40 by unfastening fastening screws 43 therefrom, rotating brush 33 axially approximately 180 degrees, and refastening screws 43 to arms 40. Brush 33 is shown as having its rearwardly disposed portion, facing the shearing head and the casing, faced off or relieved and is so shown chiefly to illustrate that the formation of the bristles may be on a suitable and relatively large radius to present sufficient bristle lengths and flexibility so as not to irritate very tender skins; however, the brush may be presented commercially in fully cylindrical form, on a shorter radius if desired, as I am well aware that in manufacture the facing off of the bristles is an extra operation and expense, and that for the user, in view of the reversibility features, less than the maximum of potential utility is presented when the brush is so faced off.

In the modification shown in Figs. 5, 6 and 7, the brush carrier has a fastening or securing portion 44a, of similar elastic material, but shorter, than previously described member 44, in the form of a single band loop, opposite ends of which are folded around rubber tubing 49a, surrounding arm portions 40a of the steel frame, of positioning member 39a. The rear portion of fastening portion 44a is a single layer of the elastic material which extends

to ends 48a as outer layer 66 and is folded to provide inner layer 67 and intermediate layer 68; the outer ends of layer 68 are folded upon themselves as as 69 to provide on each end 48a upper and lower multiple layers on the outer ends of layer 68 which form upper and lower inner shoulders 69 on ends 43a and these upper shoulders are spaced from the lower shoulders by slots 70 formed in the outer ends of layer 68; outer layer 66 is cemented to layer 68 and to tubing 49a, layer 68 is cemented to layer 67 and tubing 49a and carefully cemented to layer 67 at the inner ends of shoulders 69 and provides well defined grooves as at 71; inner shoulders 69 and their spacing slots 70 are externally covered by the outer ends of layer 67, which outer ends have been somewhat stretched in the folding and cementing operation and are under tension always, and form upper and lower casing abutting shoulders 72 on each end 48a, and, between the shoulders 72 and in the slots 70, layer 67 is cemented to tubing 49a and depressions 73 result substantially centrally between the shoulders 72 on each end 48a and thereby providing indent faces on the positioning member for vertically spaced abutting engagement of the handle and, in the case of the lower shoulders, heels or rock faces upon which the brush may be tilted outwardly from the shearing head to widen the space therebetween; tubes 49a are forcibly movable rotatably on arm portions 40a, consequently shoulders 69 are made wide enough to cause shoulders 72 to be sufficiently wide to compensate for lateral enlargement of the band loop which may result from stretching fastening portion 44a in the act of positioning it on the shaver; any inaccurate initial position of the casing abutting faces of ends 48a may easily be corrected by seizing ends 48a, pulling them outwardly from the casing and shifting them laterally as desired, and resetting ends 48a with shoulders 72 thereof in facial engagement with the side of the casing inwardly of the corners thereof. As shown in these figures, the cross portion 41a of the U-shaped frame is cylindrical in cross section throughout its length and it, arms 40a and tubes 49a may be of any suitable diameters, absolute or relative; threaded holes 42a in the upper ends of arm portions 40a are similar to, and for similar function as are, holes 42. Referring particularly to Fig. 7, it will be observed that the brush attachment is shown mounted upon a shaver having a multiplicity of shearing heads in which the outer shear members 27a have a cylindrical segment central portion provided with a series of small perforations forming shearing elements therein and have, on opposite sides of the area of small perforations, side portions diverging outwardly and terminating downwardly in substantially parallel side portions from which transverse slots 28a, in rows, extend upwardly and into the cylindrical segment central portion and form combing and shearing bars in the member 27a; in each member 27a and urged against the inner surface of its segment portion by spring pressed balls, is a hollow, cylindrical, longitudinally reciprocable, cooperating inner cutter 30a having a row of transverse slots forming shearing bars for shearing cooperation with shear members 27a; at opposite ends of the shearing heads are spring connected receptacles 65 for catching cut hairs, the expansion springs extending between the center and side heads and detachably holding receptacles 65 positioned in accommodating recesses in the casing; the upper end of the casing has its opposite side faces externally corrugated in its upper portion and on this upper end the brush carrier is mounted telescopically with fastening portion 44a thereof partially stretched by the casing, but sufficiently stretched to firmly position shoulders 72 pressed against the side face of, and adjacent the side end corners of, the casing, and with the bristles 34a of brush 33a suitably spaced from slots 28a; brush 33a, having a fully cylindrical formation of bristles 34a, may, in addition to its end-wise reversibility, be detached from positioning member 39a, rotated approximately 180 degrees to present new working portions of its bristle formation whenever desired,

and fastened, in this new position, on positioning member 39a again, on arms 40a thereof. Casing sections 20a and 21a are fastened together in the same manner as sections 20 and 21, shown in Figs. 1, 2 and 3. Brush 33a, member 39a and member 44a are otherwise similar respectively to previously described brush 33, member 39 and member 44. Devoid of the brush, the shaver shown in Fig. 7 is otherwise of a commercially well known type. The hair up-raising brush shown in these figures may be adjustably positioned to vary the height of the bristles relatively to the shearing head, for simultaneous travel therewith on the skin, or may be retracted from shaving cooperation with the head to fully expose the side of the head, similarly as described in connection with Figs. 1-4.

In Fig. 8, the shaver shown has the upper ends of the side portions of the casing inclined inwardly towards the shearing head and convexly curved, as at 74, in the same direction. In this instance fastening portion 44b, which otherwise is similar to and similarly attached to the shaver casing as previously described fastening portion 44, has its flexible arm extensions 46b and ends 48b, from the inner end 50b of the inner layers of material, of the same construction as has fastening portion 44a from end 50a thereof outwardly and previously described, and it will be observed that the upper and lower shoulders on ends 48b at opposite ends of indent portions 73a abut the externally curved face 74 of the side of the casing and position brush 33b against accidental rocking away from the shearing head or toward the shearing head and thereby preventing undesirable spacing of the bristles 34b away from the shearing head or their entrance into the slots of the head; cross portion 41b of positioning member 39a is cylindrical in cross section throughout its length and brush 33b is secured to positioning member in a similar manner and by similar means previously described; in other respects the shaver shown in Fig. 8 is similar to the shaver shown in Figs. 1, 2 and 3, and parts 20b, 21b, 22b and 32b of the former are similar to corresponding parts 20, 21, 22 and 32 of the latter.

In some instances, in order to reduce bulkiness in the fastening ends of the brush carrier, or to present a greater length to the portions of the bristles which project forwardly of the fastening ends, I may provide the brush in the form shown in Fig. 9 in which the twisted wire 35c of brush 33c is rearwardly bent as at 75 in regions spaced from and outwardly opposite the longitudinal ends of the cylindrical formation of bristles 34c and whereby the end loops 36c are disposed rearwardly of the axis A—A' of the bristle formation; these bends 75 of 35c are made far enough out longitudinally from the ends of the bristle formation so as not to loosen any of the bristles therein. Brush 33c is fully cylindrical.

In Fig. 10 there is shown in perspective a fragmentary view, with a part broken away to show parts in section and a part in elevation, of a further modification of parts of the brush carrier and in which rectangular blocks 76 of suitable material, for example suitable wood, are disposed, in ends 48c, at the rear of the arms of the U-shaped steel frame with the forward faces of blocks 76 abutting the flexible rubber tubes 49c surrounding the arms of the frame; between the upper and lower ends of blocks 76 their rear faces are indented as at 77 to provide upper and lower inner shoulders on tubular fastening ends 48c; the ends of the elastic securing member are tightly looped around blocks 76 and the frame arms, as shown, and cemented to the tubes and blocks, and layers 78 and 79 are securely cemented together, and, as a result, external upper and lower casing-abutting shoulders are formed in, and spaced by depressions 73b in, ends 48c for suitably positioning the brush relatively to the shearing head of the shaver, for example, as shown in Figs. 7 or 8. In this modification, it will be observed that the lower ends of blocks 76 provide rigid backing for lower shoulders 72c to serve as heels or rock faces upon which the brush, by inward push on the crossbar of the frame,

may be tilted or rocked outwardly from, or laterally away from, the shearing head, to widen the space between the bristles of the brush and the shearing head to a greater degree than, and for similar purpose, as has hereinbefore been described.

In Fig. 11, there is shown a fragmentary and perspective view, with a part broken away to show parts in section and a part in elevation, of a still further modification of parts of the brush carrier and in which the rigid U-shaped steel frame has its arm portions of generally rectangular shape and with their rear faces suitably indented, as shown, to provide the spaced upper and lower inner shoulders on the arm portions projecting rearwardly of the cross portion 41d, of substantially square cross-section, of the frame; the ends of the elastic securing member are tightly looped several times around the arms of the frame to provide two layers of the elastic material on the front and rear and inside sides of the arms and three layers of the elastic material on the outer sides of the arms of the frame, as shown, and, as will be observed, the innermost layers of the elastic material loops are in direct facial engagement with the metal arms of the frame; the layers are securely cemented together all around and the outer of the three layers on the outer sides of the frame are securely cemented to the paralleling faces of the intermediate layers throughout the area of the latter; the distance from the centers of the threaded fastening holes 42d, for receiving the screws to fasten the loop ends of the brush on the frame, to the external shoulders 72d is approximately the same as the distance between the corresponding parts shown in Fig. 10 and the brush is positioned on the shaver, similarly as has been shown in Figs. 7 or 8 and described in connection therewith, with shoulders 72d engaging the casing. By this modification of the positioning member, the tilting or rocking adjustment, as well as the vertical and retractive adjustments, is most easily accomplished by the user, when using his handle gripping hand, because of the better cross-section shape of the crossbar for minimizing finger slip off the bar.

In the modification shown in Figs. 12, 13 and 14, and in which the elastic loop fastening band is dispensed with, frame 39e, supporting hair up-raising brush 33e, is fastened to the casing of the multiple shearing head shaver by screws 23e which also serve as the upper fastening screws to fasten sections 20e and 21e of the shaver casing together. The upper ends of arms 40e have the threaded screw receiving holes or sockets 42e and the rear faces of the arms are suitably indented to provide upper and lower tooth-like projections 80, the rear ends of which serve as casing abutting shoulders 72e. The heads of screws 23e are seated recessed in frame arms 40e in flared end holes 81 and the shanks of the screws extend through internal posts of section 20e into threaded connection with internal posts of section 21e of the casing handle. This shaver is otherwise similar to the shaver shown in Fig. 7. If desired, the brush supporting frame may have provision for upward or downward adjustment of position on the casing as shown in Fig. 15 in which frame 39f, in arms 40f thereof, is provided with elongated holes 81a for fastening screws 23f; holes 81a extend through arms 40f; screws 23f have heads which engage the front faces of arms 40f on opposite sides of holes 81a; screws 23f otherwise function similarly as do screws 23e.

In Fig. 16, on a smaller scale, the multiple shearing head shaver is shown provided with hair up-raising brushes 33g and 33g' disposed in front of opposite sides of the shearing head. The brushes are carried by the brush positioning frames 39g and 39g' (similar to the frame shown in Fig. 11) and the arms of frames 39g are connected to the arms of frames 39g', on corresponding side ends of the shaver, by elastic strips 44g extending transversely of the opposite side ends of the shaver. Strips 44g are made of sponge rubber material, similar to the

material of previously described members 44 and 44a, and have opposite ends 48g and 48g', respectively constructed as shown in Fig. 11. Strips 44g are shown longitudinally stretched sufficiently to properly fasten the attachment 5 on the shaver with the brushes positioned for simultaneous engagement of the skin by the brushes and shearing head; whenever it is desired, during the shaving operation, to temporarily expose the front of one or the other sides of the shearing head, for example, for sideburn or 10 mustache trimming, the user may seize either ends 48g or ends 48g' and pull downwards, by further stretching of strips 44g, either of the brush positioning frames. Brushes 33g and 33g' are similar to brush 33a (Fig. 7) and the shaver is otherwise similar to the shaver shown in 15 Fig. 7.

In Fig. 17, also on a reduced scale, the hair up-raising brush attachment is shown in a form similar to the form shown in Figs. 12, 13 and 14, and may be modified as 20 shown in Fig. 15. Preferably, between each end fastening loop of brush 33h and the upper faces or upper ends 25 of the arms of frame 39h, rubber washers are inserted and whereby the washers and the loop ends of the wire of the brush are fastened together to arms 39h by the brush fastening screws to provide relatively soft rubber 30 cushions for and beneath the wire at opposite ends of the brush. Frame 39h is fastened to the casing by the spaced, removable screws extending therefrom through one section of the casing into threaded engagement with internal posts in the opposite section of the casing, and which screws serve, also, to fasten the upper portions of the casing sections together, and brush 33h is otherwise similar to brush 33e.

It will be obvious that in the structures shown in Figs. 35 12, 13, 14 and 15 rubber washers may, if desired, be employed to cushion the ends of the wire of the brush on members 39e and 39f similarly as in the structures shown in Fig. 17, and it will be clear that, in the constructions shown in Figs. 1, 2, 3, 6, 6a, 7, 8, 10, 11, and 16, the rubber surrounding the arms of the brush supporting frame 40 is substantially flush with, or otherwise high enough to, the top end faces of the frame arms to cushion the ends of the wire of the brush.

It will also be clear, that in the event the user may 45 wish to stiffen the bristles of the brush, he may do so by removing the brush from the frame and rotating the brush manually against the operating shearing head to cut the bristles shorter.

In using the word "bristles" in the claims, I wish it to be understood not in the narrow sense only as connoting only hairs and only hairs derived from animals or plants, but to include, also, any other natural or synthetic material suitable for travel on the beard and skin of a person in the manner and for the purposes which have hereinbefore been described; and, in using the word 50 "brush" in the claims, I wish it also to be understood as not being limited to an instrument composed of hair bristles, but to include, also, an instrument composed of any other material, natural or synthetic, in filament, or threadlike, or fibrelike form, which is arranged as 55 are bristles in the ordinary brush and which material and its arrangement are suitable for travel on the beard and the skin of a person in the manner and for the purposes which have hereinbefore been described.

Having described the invention, I claim:

65 1. In a dry shaver, in combination, a skin-engaging shearing head comprising relatively movable shearing members, a handle supporting the shearing head, and a hair up-raising brush having a formation of flexible bristles adapted for positive travel on the skin, said handle 70 carrying the brush with said formation of bristles thereof disposed alongside said shearing head for simultaneous and positive travel on the skin by the free ends of said bristles and by said shearing head, the shearing head being adapted for receiving hairs as it is moved on the skin 75 in the direction in which it will trail the brush, and the

bristles of said formation being adapted to be flexed by the skin, in said travel thereon, in the direction opposite to the direction in which said shearing head is moved on the skin.

2. In a dry shaver, in combination, a skin-engaging shearing head comprising relatively movable shearing members and having a hair-receiving zone, a handle supporting the shearing head, and a hair up-raising brush having a longitudinal formation of flexible bristles adapted for positive travel on the skin, said handle carrying the brush with said formation of bristles thereof disposed alongside said shearing head and spaced from said hair-receiving zone thereof for simultaneous and positive travel on the skin by the free ends of said bristles of said brush and by said shearing head, the hair-receiving zone of said shearing head being adapted for receiving hairs as said head is moved on the skin in the direction in which it will trail the brush, and the bristles of said formation being adapted to be flexed by the skin, in said simultaneous and positive travel thereon, in the direction opposite to the direction in which said shearing head is moved on the skin.

3. In a dry shaver, in combination, a skin-engaging shearing head comprising relatively movable shearing members, a handle supporting the shearing head, a hair up-raising brush having a longitudinal formation of flexible bristles adapted for positive travel on the skin, said handle carrying the brush with said formation of bristles disposed alongside said shearing head for simultaneous and positive travel on the skin by the free ends of said bristles of the brush and by said shearing head, the shearing head being adapted for receiving hairs as said head is moved on the skin in the direction in which it will trail the brush, said formation of bristles being adapted to be flexed by the skin, in said simultaneous and positive travel thereon, in the direction opposite to the direction in which said shearing head is moved on the skin, and a second formation of flexible bristles in said brush projecting angularly of the first recited formation of bristles and in a direction laterally outwardly relatively to the shearing head for engagement with the skin prior to the engagement of the skin by the shearing head for brushing foreign matter from the beard and skin.

4. In a dry shaver, in combination, a skin-engaging shearing head comprising relatively movable shearing members and having a hair-receiving zone, a handle supporting the shearing head, a hair up-raising brush having a longitudinal formation of flexible bristles adapted for positive travel on the skin, said handle carrying the brush with said formation of bristles disposed alongside said shearing head and spaced from said hair-receiving zone thereof for simultaneous and positive travel on the skin by the free ends of the bristles in said formation of said brush and by said shearing head, the hair-receiving zone of said shearing head being adapted for receiving hairs as said head is moved on the skin in the direction in which it will trail the brush, said bristles being adapted, with said brush in advance of said head in said simultaneous and positive travel on the skin, to be flexed by the skin towards said shearing head with said bristles spaced from said hair-receiving zone of said shearing head, and a second formation of flexible bristles in said brush projecting angularly of the first recited formation of bristles and in a direction laterally outwardly relatively to the shearing head for engagement with the skin prior to the engagement of the skin by the shearing head for brushing foreign matter from the beard and skin.

5. In a dry shaver, in combination, a skin-engaging shearing head comprising relatively movable shearing members, a handle supporting the shearing head, a hair up-raising brush having a longitudinal formation of flexible bristles adapted for positive travel on the skin, means carried by the handle supporting the brush with said for-

mation of bristles thereof disposed alongside said shearing head for simultaneous and positive travel on the skin by the free ends of said bristles in said formation of the brush and by said shearing head, the shearing head being adapted for receiving hairs as said head is moved on the skin in the direction in which it will trail the brush, the bristles in said formation being adapted to be flexed by said simultaneous and positive travel on the skin in the direction opposite to the direction in which said shearing head is moved on the skin, and said means supporting said brush vertically adjustable as to its height relatively to the shearing head for varying the height to which said free ends of the bristles extend relatively to the shearing head for said simultaneous and positive travel on the skin by said free ends of the bristles and by said shearing head.

6. In a dry shaver, in combination, a skin-engaging shearing head comprising relatively movable shearing members and having a hair-receiving zone, a handle supporting the shearing head, a hair up-raising brush having a longitudinal formation of flexible bristles adapted for positive travel on the skin, means carried by the handle supporting the brush with said formation of bristles thereof disposed alongside said shearing head and spaced from said hair-receiving zone thereof for simultaneous and positive travel on the skin by the free ends of said bristles and by said shearing head, the hair-receiving zone of said head being adapted for receiving hairs as said head is moved on the skin in the direction in which it will trail the brush, the bristles of said formation being adapted to be flexed by the skin, in said simultaneous and positive travel thereon, in the direction opposite to the direction in which said head is moved on the skin, and said means supporting said brush for outward tilting movement laterally away from said shearing head to widen the space between said formation of bristles of the brush and said hair-receiving zone of said shearing head for said simultaneous and positive travel on the skin by said free ends of the bristles and by said shearing head.

7. In a dry shaver, in combination, a skin-engaging shearing head comprising relatively movable shearing members, a handle supporting the shearing head, a hair up-raising brush having a longitudinal formation of flexible bristles, means carried by the handle supporting the brush with said formation of bristles thereof disposed alongside said shearing head for simultaneous and positive travel on the skin by the free ends of said bristles and by said shearing head, the shearing head being adapted for receiving hairs as said head is moved on the skin in the direction in which it will trail the brush, said formation of bristles being adapted to be flexed by the skin, in said simultaneous and positive travel thereon, in the direction opposite to the direction in which said shearing head is moved on the skin, and said means supporting said brush movable for retraction from shaving cooperation with the head and away from said shearing head to fully expose the side thereof.

8. In a dry shaver, in combination, a skin-engaging shearing head comprising relatively movable shearing members and having a hair-receiving zone, a handle supporting the shearing head, a hair up-raising brush having a longitudinal formation of flexible bristles adapted for positive travel on the skin, means carried by the handle supporting the brush with said formation of bristles thereof disposed alongside said shearing head and spaced from said hair-receiving zone thereof for simultaneous and positive travel on the skin by the free ends of the bristles in said formation of said brush and by said shearing head, the hair-receiving zone of said head being adapted for receiving hairs as said head is moved on the skin in the direction in which it will trail the brush, said bristles being adapted, with said brush in advance of said head in said simultaneous and positive travel on the skin, to be flexed by the skin towards said shearing head, the hair-receiving zone of said head being adapted for receiving hairs as said head is moved on the skin in the direction in which it will trail the brush, said bristles being adapted, with said brush in advance of said head in said simultaneous and positive travel on the skin, to be flexed by the skin towards said shear-

ing head with said bristles spaced from said hair-receiving zone of said head, and said means supporting the brush vertically adjustable relatively to the shearing head for said simultaneous and positive travel and tiltable outwardly away from said head to widen the space between said formation of bristles and said head for said simultaneous and positive travel and also supporting said brush movable for retraction from shaving cooperation with the head and away from said shearing head to fully expose the side thereof.
